UNITED STATES PATENT OFFICE.

PLUMMER DOUGLAS SCARBOROUGH, OF SYRACUSE, NEW YORK.

NOVELTY-HOLDER.

1,326,099.

Specification of Letters Patent. Patented Dec. 23, 1919.

Application filed June 11, 1919. Serial No. 303,359.

To all whom it may concern:

Be it known that I, PLUMMER DOUGLAS SCARBOROUGH, a citizen of the United States, residing at Syracuse, in the county of 5 Onondaga, State of New York, have invented certain new and useful Improvements in Novelty-Holders; and I do hereby declare the following to be a full, clear, and exact description of the invention, such as 10 will enable others skilled in the art to which it appertains to make and use the same.

This invention relates to the class of card, picture and sign exhibiting stands and more particularly to an improved supporter for 15 envelopes on display cards, which is attachable to fit the size of the display novelty so as to support packages of headache powders, corn plasters, perfumes and the like.

The object of the invention is to provide 20 a supporter which can be stamped from a blank section of material and bent to provide tapered or pointed piercing portions designed to be pushed through the display card so as to be securely held in position for 25 supporting the article or novelty to be displayed.

With the above objects and others in view as will appear as the specification proceeds, the invention comprises certain novel combinations and arrangements of parts as will 30 be hereinafter more particularly pointed out and claimed.

Reference is had to the accompanying drawings forming a part of this application, 35 wherein like characters designate corresponding parts throughout the several views, in which—

Figure 1 is a side elevation showing my improved supporter in use,

Fig. 2 is a plan view of the device enlarged,

Fig. 3 is an enlarged edge view, and

Fig. 4 is a perspective view of the device.

Referring to the drawings in detail, my 45 improved spreader is shown as comprising a triangular section 10 of suitable material such as tin, nickel, wood or the like but preferably tin. The sides 11 of the triangular plate or blank are considerably longer than 50 the base edge 12, thus providing a tapered or pointed piercing end 13 at the apex thereof.

Stamped from the plate is a tongue or bur 14 which is shaped similarly to the 55 plate, that is the sides or side edges 15

thereof are substantially parallel to the sides or side edges 11, thus providing a tapered piercing end or point 16 extending in the same direction as the end 13. The base of the substantially triangular bur or 60 tongue is unsevered as shown at 17 and on a line connecting the base ends of the sides 15 produced by the V-shaped incision or cut in the plate, the tongue is bent downwardly at an acute angle as clearly shown in Figs. 65 1 and 3 of the drawings.

The opposed edges 11 are provided with a series of V-shaped notches 18 with the walls thereof disposed toward the end 13 arranged in alined transverse series or in alinement 70 so that lines connecting the apexes thereof will lie parallel to the base 12. These notches are thus equidistantly spaced apart and extend throughout a greater portion of the lengths of the sides 11 beginning at the 75 end portion 13.

Thus, the device may be applied to a display card or easel 19 having the usual support 20 by pushing or passing the end portions 13 and 16 through the display card 80 near the top thereof so that the plate proper will lie substantially horizontal while the tongue 14 will extend downwardly at an acute angle and brace the supporter in position for holding novelties or the like. The 85 device may be made in various sizes as needed and obviously, may be very cheaply manufactured by reason of being stamped from sheet material of a resilient or other nature. The tongue effectively holds the 90 device in position and the notches prevent withdrawal of the plate when the card is once pierced, due to the flexibility and pliable nature of the card itself.

It should also be noted that the edge portion 95 at the base 12 is bent or turned upwardly as shown at 12', in order to retain the envelopes or the like 21 in position against displacement. It should be noted from Fig. 1 of the drawings that the envelopes will rest upon the holder and against the card 19 and it will also be apparent that the device may be arranged to support any desired number of envelopes or packets according to the degree at which the device is 100 forced through the display card and held against displacement as heretofore described. Furthermore, the turned-up edge 12' may be employed for printing thereon 105 suitable advertising matter or other indicia, 110

such as the manufacturer's name or the like.

What is claimed is:—

1. A supporter of the class described comprising a triangular plate of flexible material having a V-shaped incision forming a tapered tongue extending in the same direction as the tapered end of the plate and bendable at its base portion, said plate having means to prevent withdrawal thereof when pushed through a display card.

2. A supporter comprising a tapered plate of sheet material having notches in the sides thereof forming retaining means and a tapered tongue stamped in the plate.

3. A supporter for novelties on display cards comprising a triangular plate of resilient metal having a V-shaped cut forming a tapered tongue of substantially triangular outline with the apex thereof extending in the direction of the apex of the plate and its sides substantially parallel to the sides of the plate, said tongue being bendable at its base portion from the plate 25 to extend at an acute angle with respect thereto and the opposed sides of the plate having spaced notches, common sides of

which are in alinement and parallel to the base of the plate.

4. The combination with an easel of paste board, of a supporter comprising a triangular plate and a tapered tongue extending at acute angles from the plate, the side edges of the plate having opposed pairs of notches extending from the tapered end of the plate 35 throughout a greater portion of the lengths of said sides and with opposed pairs equidistantly spaced from said end whereby when said end and tongue are pushed through the card, the supporter will be held 40 from displacement.

5. A holder of the class described comprising a tapered plate having a turned-up edge and a tongue stamped from the plate to extend downwardly at an angle, said 45 plate having means to prevent its displacement when passed through a display card together with said tongue.

In testimony whereof I affix my signature in the presence of two witnesses.

PLUMMER DOUGLAS SCARBOROUGH.
